UNITED STATES PATENT OFFICE.

CHARLES H. JOCKMUS, OF ANSONIA, CONNECTICUT.

PERCUSSION-SHELL FUSE.

1,309,479.

Specification of Letters Patent.

Patented July 8, 1919.

Application filed July 16, 1917. Serial No. 180,704.

To all whom it may concern:

Be it known that I, CHARLES H. JOCKMUS, a citizen of the United States, residing at Ansonia, county of New Haven, State of Connecticut, have invented an Improvement in Percussion-Shell Fuses, of which the following is a specification.

This invention relates to percussion shell fuses, and has for its objects the prevention of accidental explosion of the shell while fitting the fuse and while handling, the prevention of premature explosion in the gun or near the muzzle of the gun when the firing charge in the gun is exploded, and the provision of mechanism which will arm the fuse by inertia of the firing plunger, when the firing charge is exploded, but will effectively retain the firing plunger away from the primer, and when the projectile strikes an objective will positively function and detonate the primer.

These results I accomplish in the manner which I will now describe, referring to the accompanying drawing forming a part of this specification and using reference characters to indicate the several parts.

Figure 1 is an end view of my novel fuse as seen from the left in Fig. 2;

Fig. 2 a section on the line 2—2 in Fig. 1 looking in the direction of the arrows;

Fig. 3 an end view as seen from the right in Fig. 2;

Fig. 4 a sectional view corresponding with Fig. 2, showing the position of the parts after the fuse has been armed by explosion of the firing charge;

Fig. 5 a similar view showing the position of the parts when the fuse has functioned upon impact of the shell;

Fig. 6 a section on the line 6—6 in Fig. 2, looking in the direction of the arrows;

Fig. 7 a section on the line 7—7 in Fig. 4, looking in the direction of the arrows;

Fig. 8 a perspective view of the firing plunger and safety device, the parts being unattached to each other;

Fig. 9 a similar view showing a slightly modified form in which the safety device is secured to the firing plunger, and

Fig. 10 is a view showing a slightly modified form of cap which is provided with a chamber to receive an accelerating charge.

20 denotes the body of the fuse having the usual chamber 21 which is closed by a cap 22, shown as resting against a shoulder in the body and retained in place by spin-

ning the open end of the body over it. At the inner end of the chamber is an inwardly extending projection 23, which is preferably made in the form of a frustum of a cone. 60 The cap is provided with the usual pocket to receive a primer 24, and surrounding the pocket is a concentric groove 25, leaving a circular rib 40 between the groove and the pocket. 26 denotes the firing plunger which 65 is provided at its forward end with a depression 36 at the center of which is a point 27, in its base with a conical recess 28, the edge of which preferably terminates in a flange 29, and in its sides with oppositely lying 70 longitudinal grooves 30. The firing plunger is normally prevented from arming and is retained with the point at a safe distance from the primer by means of a safety device, indicated as a whole by 31. This 75 safety device is made from resilient sheet metal and comprises a ring 32, spring arms 33 extending therefrom and lying in the grooves, and curved heads 34 at the other ends of the arms which normally lie between the plunger and the circular rib and 80 dog the plunger. These heads are provided with engaging projections 37, shown as formed by doubling the metal upon itself.

In assembling, the firing plunger is placed 85 between the spring arms of the safety device, with the ring lying within the flange at the base of the plunger, the arms lying in the grooves and springing toward each other and the heads lying in the depression on opposite sides of the point, see Fig. 6 in connection with Fig. 2. If preferred, and in order to prevent lost motion between the firing plunger and the safety device, the ring may be locked in place by spinning or 90 indenting the edge of the flange over the ring as shown at 35 in Fig. 9. It will be obvious, however, that the safety device will be self retaining upon the firing plunger without spinning or indenting the flange 100 upon the ring. The firing plunger and safety device are then placed in the chamber and the cap is secured in place. It will be noted, see Fig. 2, that projection 23 at the inner end of the chamber is in alinement 105 with the opening in the ring, that the arms 33 spring inward, their outer ends engaging the bottoms of the grooves, and that the heads at the outer ends of the arms are in position to engage circular rib 40 on the cap 110 if the firing plunger moves forward.

Shells provided with my novel fuses may

be handled with safety and fitted with fuses, accidental explosion being practically impossible, and when subjected to the drop test the safety device is found to effectually 5 prevent the fuse from arming. This protection against explosion when the shell is dropped is rendered doubly sure owing to the fact that the engaging projections on heads 34 overhang the edge of the depression 10 36 in the forward end of the firing plunger, the effect of the incline of the depression being not only to lock the heads against moving apart (which would arm the fuse) but to actually crowd the heads inward toward 15 the point. When the shell is impelled forward, however by the shock of the explosion of a firing charge in a gun, the inertia of the firing plunger will cause projection 23 at the inner end of the chamber to pass 20 into the ring and cup the ring, the effect of which is to throw the spring arms and the heads outward against the wall of the chamber, so that while the fuse is effectively 25 armed, see Fig. 4 in connection with Fig. 7, any creeping forward or rebounding of the firing plunger is prevented by the frictional engagement of the heads with the wall of the chamber. This makes premature explosion in the gun or near the muzzle of 30 the gun practically impossible. When, however, the shell strikes an objective the impact instantly overcomes the frictional resistance of the spring arms, and the firing plunger is thrown forward violently, the 35 heads of the spring arms passing into groove 25 in the cap and the point detonating the primer, as indicated in Fig. 5.

Having thus described my invention, I claim:—

- 40 1. A fuse of the character described, comprising a body having a chamber with a projection at its inner end, a cap closing the chamber and having a primer pocket, a circular groove and a rib between the groove and the pocket, a firing plunger having a recess in its base, grooves in its sides and a point, and a resilient safety device consisting of a ring lying in the recess and arms lying in the grooves and having heads lying between the plunger and the rib, the shock of 45 explosion of a firing charge causing the projection to arm the fuse by cupping the ring, the heads being thrown into engagement with the wall of the chamber to prevent creeping or rebounding of the plunger and impact with an objective causing the plunger to overcome the frictional resistance of the safety device, the heads passing into the circular groove and the point detonating a 50 primer.
- 60 2. A fuse of the character described, comprising a chamber having a projection at its inner end, a cap closing the chamber and having a primer pocket, a firing plunger 65 having a recess in its base and grooves in

its sides, and a safety device comprising a ring seated in the base of the plunger, and having spring arms lying in the grooves, and heads, which normally prevent arming, the inertia of the firing plunger, when the 70 firing charge in a gun is exploded, causing the projection to cup the ring and throw the heads into engagement with the wall of the chamber to prevent creeping or rebounding of the plunger. 75

3. A fuse of the character described, comprising a body having a projection, a cap closing the body and adapted to receive a primer, a firing plunger having a recess co-operating with the projection, and a safety 80 device on the plunger comprising a ring and spring arms having heads which normally prevent arming, and after explosion of a firing charge and cupping of the ring by the projection prevent creeping or rebounding 85 of the plunger.

4. A fuse of the character described, comprising a body having a projection, a firing plunger having a recess co-operating with the projection, and a safety device on the 90 plunger comprising a ring and spring arms having heads which normally prevent arming, and after explosion of a firing charge and cupping of the ring by the projection prevent creeping or rebounding of the plunger. 95

5. A fuse of the character described, comprising a chambered body having a projection, a primer carrying cap which closes the chamber, a firing plunger having a recess 100 co-operating with the projection, and a safety device on the plunger comprising a ring and spring arms having heads which normally prevent arming, explosion of a firing charge causing the projection to cup the ring 105 and throw the heads against the wall of the chamber to prevent creeping or rebounding of the plunger, and impact causing detonation of a primer.

6. A fuse of the character described, comprising a chambered body having a projection, a cap closing the chamber and having a primer pocket, a concentric groove, and a circular rib between the groove and the pocket, a firing plunger having a recess co-operating with the projection, and a safety device on the plunger comprising a ring and 110 spring arms having heads which normally lie between the plunger and the circular rib, and when the ring is cupped by the projection and recess engage the wall of the chamber, for the purpose set forth, the heads upon impact entering the groove and permitting detonation of a primer. 115 120

7. A fuse of the character described, comprising a chambered body having a projection, a cap closing the chamber and having a primer pocket, a concentric groove and a circular rib between the groove and the pocket, a firing plunger having a recess co- 125 130

- operating with the projection, and longitudinal grooves, and a safety device on the plunger comprising a ring and spring arms lying in the grooves and having heads which normally lie between the plunger and the circular rib, and when the ring is cupped by the projection engage the wall of the chamber.
8. A fuse of the character described, comprising a chambered body having a projection, a cap closing the chamber and having a primer pocket, a circular rib and a circular groove, a firing plunger having a recess coöperating with the projection and a point, and a safety device on the plunger comprising a ring and spring arms having heads which normally prevent arming by engagement with the rib, explosion of a firing charge acting to cup the ring and throw the head against the wall of the chamber to prevent creeping or rebounding of the plunger, and impact causing the heads to enter the groove and the point to detonate a primer in the pocket.
9. A fuse of the character described, comprising a chambered body having a projection, a firing plunger having a recess coöperating with the projection, the edge of said recess terminating in a flange, and a safety device on the plunger comprising a ring and spring arms having heads which normally prevent arming and after cupping of the ring prevent creeping or rebounding of the plunger, said safety device being locked to the plunger by spinning or indenting the flange over the ring.
10. A fuse of the character described, comprising a chambered body having a projection, a cap having a primer pocket, a circular rib and a circular groove, a firing plunger having a recess coöperating with the projection, and a safety device on the plunger comprising a ring and spring arms having heads which normally prevent arming by engagement with the circular rib, and after cupping of the ring prevent creeping or rebounding of the plunger by engagement with the wall of the chamber.
11. A fuse of the character described, comprising a chambered body having a projection, a firing plunger having a recess coöperating with the projection, and a safety device secured to the plunger and comprising a ring and spring arms having heads which normally prevent arming and after cupping of the ring by the projection prevent creeping or rebounding of the plunger by engagement with the wall of the chamber.
12. A fuse of the character described, comprising a chambered body having at its inner end a frustum shaped projection, a firing plunger having a cone-shaped recess adapted to coöperate with the projection, and a safety device on the plunger comprising a ring and spring arms having heads which normally prevent arming and after cupping of the ring by the projection prevent creeping or rebounding of the plunger.
13. A fuse of the character described, comprising a chambered body having a frustum shaped projection, a cap having a primer pocket, a circular rib and a circular groove, a firing plunger having a cone-shaped recess adapted to coöperate with the projection, and a safety device on the plunger comprising a ring and spring arms having heads which normally prevent arming by engagement with the circular rib, and by cupping of the ring are adapted to enter the groove but prevent creeping or rebounding of the plunger until impact by frictional engagement with the wall of the chamber.
14. A fuse of the character described, comprising a body having a projection, a firing plunger having a recess in its base coöperating with the projection, and in its forward end a depression and a central point, and a safety device comprising a ring lying in the recess and spring arms having heads with engaging projections which overhang the edge of the depression, for the purpose set forth.
15. A fuse of the character described, comprising a chambered body having at its inner end a frustum shaped projection, a firing plunger having a cone-shaped recess adapted to coöperate with the projection, grooves in its sides and at its forward end a depression and a central point, and a safety device comprising a ring lying in the recess and spring arms lying in the grooves and having heads with projections adapted to engage the inner edge of the recess, whereby the heads are locked against outward movement and arming is prevented.
16. In a fuse, the combination of a chambered body having a projection, a firing plunger having a recess coöperating with the projection, and a safety device on the plunger adapted to be armed by coöperation of said projection and recess.
17. In a fuse, the combination of a chambered body having a projection, a firing plunger having a recess coöperating with the projection, and a safety device on the plunger comprising a ring and spring arms having heads which normally prevent arming, and after arming by coöperation of the projection and recess prevent creeping or rebounding of the plunger.

In testimony whereof I affix my signature.
CHARLES H. JOCKMUS.
